ATTORNEY

UNITED STATES PATENT OFFICE

THOMAS J. BAUGH, OF HOPKINSVILLE, KENTUCKY

DESIGN FOR AN AUTOMOBILE TRAFFIC SIGNAL

Application filed August 10, 1931. Serial No. 40,807. Term of patent 7 years.

To all whom it may concern:

Be it known that I, THOMAS J. BAUGH, a citizen of the United States, residing at Hopkinsville, in the county of Christian and State of Kentucky, have invented a new, original, and ornamental Design for Automobile Traffic Signals, of which the following is a specification, reference being had to the accompanying drawings, forming part thereof.

Figure 1 is a face view of an automobile traffic signal, showing my new design.

Figure 2 is an elevation of the same.

I claim:

The ornamental design for an automobile traffic signal, substantially as shown.

THOMAS J. BAUGH.
